UNITED STATES PATENT OFFICE.

JOHN B. NIXON, OF PALMETTO, AND SMITH F. KRUPP, OF ATLANTA, GEORGIA.

COTTON CONDENSER AND REGULATOR.

1,079,949.

Specification of Letters Patent.

Patented Dec. 2, 1913.

Application filed September 27, 1912. Serial No. 722,598.

To all whom it may concern:

Be it known that we, JOHN B. NIXON and SMITH F. KRUPP, both citizens of the United States, and residents, respectively, of Palmetto, in the county of Campbell and State of Georgia, and of Atlanta, in the county of Fulton and State of Georgia, have invented a new and Improved Cotton Condenser and Regulator, of which the following is a full, clear and exact description.

The object of the invention is to provide a new and improved cotton condenser and regulator arranged to insure a bat of uniform thickness and width, to prevent the screen drum from being clogged up by the cotton fibers, to allow the use of a comparatively small condenser with a given number of gins, and to facilitate the separation of the air and dust from the fibers.

For the purpose mentioned use is made of a casing containing a concentric screen drum forming with the casing a passage for the lint, the casing having an inlet for the lint and air arranged to direct the lint against the inner surface of the casing and away from the peripheral face of the drum to facilitate the separation of the air and dust from the lint and to prevent the lint from coming in contact with the drum. Use is also made of a cylindrical deflector eccentrically within the drum for regulating the currents of air to insure a distribution of lint in the passage with a view to form a bat of even thickness.

A practical embodiment of the invention is represented in the accompanying drawings forming a part of this specification, in which similar characters of reference indicate corresponding parts in all the views.

Figure 1 is a side elevation of the cotton condenser and regulator; Fig. 2 is an enlarged transverse section of the same on the line 2-2 of Fig. 1; Fig. 3 is an enlarged sectional side elevation of the same on the line 3-3 of Fig. 2; and Fig. 4 is a front end elevation of part of the machine.

Within the cylindrical casing A is arranged a screen drum B forming with the inner surface of the casing A a passage C for the lint and air, and into the said passage C opens an inlet D connected with one or more gins and with an air supply to force the lint into the passage C and through the same to an outlet E, as plainly indicated in Fig. 3. At the outlet E are arranged doffing rollers F and F' between which passes

the lint to be pressed into a bat discharged over the chute G to a suitable receptacle. The doffing roller F is journaled in stationary bearings arranged on the casing A, and the roller F has its peripheral face in close proximity to the peripheral face of the drum B. The other roller F' is journaled in levers H fulcrumed at H' and provided with angular arms H² carrying weights H³ adjustably secured in place by set screws H⁴. Thus by the arrangement described, the doffing roller F' is forced toward the doffing roller F to press the lint into a bat of a desired thickness.

The inlet D has its bottom D' tangential with the peripheral surface of the casing A while the top D² is curved, as indicated in Fig. 3, to cause the lint to pass into the outer portion of the passage C, that is, against the inner surface of the peripheral face of the casing A and away from the peripheral face of the screen drum B. By this arrangement the screen drum B is practically kept free from lint and open for free egress of the air and dust, that is, the air is mostly between the peripheral face of the screen drum B and the lint and comes in contact with the drum first and passes through the meshes without any resistance.

It is understood that by the arrangement described, the peripheral face of the screen drum B is not liable to be clogged up by the lint, and the air is not retarded, and hence the condenser can work at all times to its full capacity. It will also be noticed that by directing the air and lint in the manner described the screen is kept comparatively free of lint, and the lint passes freely through the condenser, thus preventing banking and clogging of the gins.

The ends of the drum B extend in openings formed in transverse partitions A' and A² held on the casing A, and the ends of the drum B open into outlet chambers I and I' arranged on the ends of the casing A. Either of the outlet chambers I, I' may be provided with an outlet J for conducting air and dust to a suitable place of discharge. As shown in the drawing, the outlet chamber I is provided with the outlet J.

On the shaft B' of the drum B and within the latter are secured collars K, K spaced suitable distances apart and supporting a tubular or cylindrical deflector L in such a manner that the deflector is eccentrically suspended in the drum B. The ends of

the deflector L are open and one end is adjacent the outlet chamber I, and the deflector L is of a length less than the length of the drum B so that the incoming air and lint are uniformly distributed in the passage C to the full width thereof to insure the formation of a bat of uniform thickness and width. It will be noticed that a portion of the air entering the drum B passes through the open end thereof into the outlet J while the remaining portion of the air passes through the deflector L to the outlet J, and hence the air is more equally distributed and the lint is not liable to be massed in the end of the chamber C adjacent the chamber I, but is equally distributed in the chamber C to form a bat of uniform thickness.

It is understood that the deflector L is for the purpose of balancing the air current so that the lint is distributed equally the same depth and thickness along the full length of the doffing rollers F, F' with a view to produce a bat of full width and even thickness. It is also understood that the shaft B' is connected with suitable machinery for imparting a rotary motion to the drum B, and the doffing roller F is driven from the shaft B' by sprocket wheels and chain, or other driving means.

Having thus described our invention, we claim as new and desire to secure by Letters Patent:

1. A condenser, comprising a casing, a screen drum arranged within the casing and forming with the same a passage for the lint, and an inlet connected with one or more gins and an air supply, and opening into the said passage tangentially relative to the inner surface of the casing to direct the lint against the inner casing surface and away from the peripheral face of the said drum, the said passage having an outlet, doffing rollers in the said outlet, and a tubular deflector eccentrically suspended within the said drum and open at both ends.

2. A condenser, comprising a casing, a screen drum arranged within the casing and forming with the same a passage for the lint, and an inlet connected with one or more gins and an air supply, and opening into the said passage tangentially relative to the inner surface of the casing to direct the lint against the inner casing surface and away from the peripheral face of the said drum, an outlet at one end of the casing, an outlet leading from the said passage, doffing rollers in the said outlet, collars on the shaft of the said drum within the latter, and a tubular deflector supported on the said collars and open at its ends.

3. A condenser, comprising a casing, a

screen drum arranged within the casing and forming with the same a passage for the lint, and an inlet connected with one or more gins and an air supply, and opening into the said passage tangentially relative to the inner surface of the casing to direct the lint against the inner casing surface and away from the peripheral face of the said drum, an outlet at one end of the casing, an outlet leading from the said passage, doffing rollers in the said outlet, collars on the shaft of the said drum within the latter, and a tubular deflector supported on the said collars and open at its ends, one open end of the said deflector being adjacent the end of the casing at the said casing outlet.

4. A condenser, comprising a casing, a screen drum arranged within the casing and forming with the same a passage for the lint, and an inlet connected with one or more gins and an air supply, and opening into the said passage tangentially relative to the inner surface of the casing to direct the lint against the inner casing surface and away from the peripheral face of the said drum, an outlet at one end of the casing, an outlet leading from the said passage, doffing rollers in the said outlet, collars on the shaft of the said drum within the latter, and a tubular deflector eccentrically supported on the said collars and open at its ends, the said deflector being of a length somewhat less than the length of the said drum.

5. A condenser, comprising a casing having an inlet and an outlet for the cotton at the peripheral face of the casing and an outlet at the side of the casing for the air and dust, a screen drum concentrically within the casing and forming with the latter a passage between the cotton inlet and outlet, and a tubular deflector arranged eccentrically within the drum.

6. A condenser, comprising a casing having an inlet and an outlet for the cotton at the peripheral face of the casing and an outlet at the side of the casing for the air and dust, a screen drum concentrically within the casing and forming with the latter a passage between the cotton inlet and outlet, and a tubular deflector arranged eccentrically within the said drum and open at both ends, one open end being opposite the said air and dust outlet.

In testimony whereof we have signed our names to this specification in the presence of two subscribing witnesses.
